REINFORCEMENT OF RIVETED ELECTRICAL CONNECTIONS

Dario Domizi, Darien, Conn., and George E. Cranch, Fostoria, Ohio, assignors to Union Carbide Corporation, a corporation of New York

Filed June 9, 1958, Ser. No. 740,607
2 Claims. (Cl. 310—249)

This invention relates to reinforced electrical connections and methods of producing the same. More particularly, this invention relates to reinforcing a riveted shunt connection to an electrical contact brush.

Riveted brush shunt connections have long been known to the art. Such connections are usually made by drilling a hole through the brush, counterboring the hole on one side of the brush, forming an eyelet or loop on the end of the shunt, placing the eyelet in the counterbore, inserting a tubular rivet blank through the eyelet and through the drilled hole and then establishing the connection by spinning both ends of the blank to form rivet heads in situ.

A major disadvantage of this construction arises from the fact that it is difficult to control the degree of mechanical tightness of connections at the proper level when manufacturing the riveted brushes in large quantity. If the rivet heads are not spun down tight enough, the connection may become easily loosened when the brush undergoes vibration encountered during service. When the rivet heads are spun down too tightly the relatively weak carbonaceous brush structure may crack in the area surrounding the counterbored rivet hole during the spinning operation.

A further disadvantage of the riveted type brush connection arises from the practical manufacturing necessity of maintaining a reasonably large clearance between the body of the rivet and the drilled hole in the brush when large numbers of connections are assembled. With this clearance and under the condition of severe vibration, which may accompany brush operation, the connection is sometimes caused to become so loose as to be rendered electrically useless and damage may even reach the point of actual breakage of the brush at the point where the shunt is riveted. It has been found that by keeping the rivet itself fixed in relation to the brush and allowing the brush and rivet to vibrate as a unit much of the stress on the brush at the rivet connection is relieved, and connection life is accordingly improved.

It is an object of this invention to provide a reinforced rivet connection to an electrical contact brush.

It is another object of this invention to provide a method of reinforcing a riveted brush connection which renders it relatively insensitive to normal vibration encountered during service.

In the accompanying drawings:

FIG. 1 is a perspective view of a brush embodying this invention with part of the brush cut away;

FIG. 2 is similar to FIG. 1 showing one method of introducing a reinforcing cement into a riveted brush connection;

FIG. 3 is similar to FIG. 2 showing another method of introducing the cement;

FIG. 4 is similar to FIG. 2 showing a further method of introducing the cement; and

FIG. 5 is similar to FIG. 2 showing still another method of introducing the cement.

In accord with the above objects, this invention broadly comprises the provision of a cementitious material between the rivet and the brush body of a rivet-connected brush. While the cementitious material may generally be of any type and it may be introduced between the rivet

2

and the brush body by a variety of means, certain materials introduced in particular ways have been found to perform very well in the practice of this invention.

Organic cements, such as self-hardening polymeric materials of the thermosetting type, mineral cements and molten metals, which solidify upon cooling to above the brush operating temperature, have been found to be entirely satisfactory materials. Any of these may be suitably provided between the brush body and the rivet by any of the means hereinbelow described with reference to the accompanying drawing.

A complete reinforced riveted connection is shown in FIG. 1 and consists of a brush body 10 with a hole drilled therethrough which is provided with a slotted counterbore recess into which is seated a cable eyelet 12 which terminates the electrical shunt 14. A metal shank washer 16 is placed over the cable eyelet, and a hollow rivet blank 17 is inserted through the eyelet-shank washer-brush body assembly. A metal washer 15 is placed over the rivet blank 17 and against the brush body 10 opposite the side of said brush body 10 having said counterbore recess. The rivet heads 18 and 19 are then formed by spinning, thus securely holding the eyelet 12 in intimate contact with the brush body at the interface 20. Of course, one head of the rivet blank 17 may be spun prior to insertion of said rivet blank 17 into said hole in said brush body 10. In this case, the assembly is bound to intimate contact by spinning the remaining unspun end of rivet blank 17 instead of spinning both heads at once, as described above. The cement 22 may be introduced into the assembly in a variety of ways.

Referring to FIG. 2, for example, the cement 22 may be introduced between the rivet body 17 and the brush body 10 through a hole 24 in the rivet 17 after the rivet heads 18 and 19 are spun. Or, as shown in FIG. 3 the cement 22 may be introduced between the rivet 17 and the brush body 10 through a hollow needle 28 inserted parallel with the electrical lead 14. Here again, the cement 22 is inserted after the rivet heads 18 and 19 are formed. In the modification illustrated by FIG. 4, the cement 22 is introduced between the rivet 17 and the brush body 10 through a hole 30 in the brush body 10 which extends to the rivet 17. The cement 22 is inserted after the rivet heads 18 and 19 are spun in place. Another way of practicing the invention is illustrated in FIG. 5, where the cement 22 is coated on the rivet body 17 prior to insertion thereof into the brush body 10. The rivet 17 with one head 19 spun, is then inserted and the other head 18 is spun in place.

In each case, the cement is hardened in situ after the electrical connection has been secured by the rivet.

It is an important consideration in the practice of this invention that when a non-conducting cement is used for reinforcing purposes, it must be introduced in such a manner as not to interfere with the electrically contacting surfaces of the brush body and shunt eyelet. In order to protect against this contingency, the cementitious material should preferably be added after the rivet is in place and good electrical contact has been established. Another important consideration of this invention is the choice of the materials to secure the rivet to the brush body.

While a self-hardening phenolic resin is preferred as the cement to be used in this invention, any material conductive or non-conductive, which has mechanical strength at least equal to that of the brush body and which has cementing properties through the operating temperature range of the brush may be used successfully.

Examples of some of these materials are melamine-aldehyde condensation products, epoxy and polyester resins, solidified metals added in the molten state, acrylic-

3

nitrile polymers and others. In some cases it is found advantageous to incorporate inorganic materials in the form of powders into the resin bonded cement in order to modify the plasticity of the cement as it is applied and to impart greater strength, or conductivity, after it has hardened. Suitable materials are metal powders, carbon or graphite powders, powdered talc, silica or other well known cement fillers. Self hardening silicate-bonded iron-powder cements are also suitable.

Brush connections made according to this invention were tested on a vibration tester and the results obtained were compared with results of similar tests run on brushes of conventional riveted construction. The data taken from these tests showed that brushes reinforced with a cementitious material according to this invention had an average life of 11 million impacts before loosening occurred. Conventional rivet connected brushes tested under the same conditions lasted through an average of only 940 thousand impacts before loosening occurred. Thus, it may be readily seen that the useful life of rivet connected brushes made according to this invention was about 12 times that of conventionally riveted brushes.

What is claimed is:

1. In a riveted electrical brush connection which comprises a brush body provided with a hole therethrough and an eyelet of an electrical shunt seated over and around said hole, said brush body and said eyelet of said shunt being bound together by a rivet which extends

5 through said hole and which is spun over onto said connection at both ends thereof; the improvement which comprises a cementitious material located between said brush body and said rivet and in contact with substantially the entire adjacent surfaces of said brush body and said rivet.

10 2. The improvement as defined in claim 1 wherein said cementitious material is chosen from the group consisting of a self-hardening plastic, a thermo-setting resin, a phenol-formaldehyde condensation product, and a metallic material which remains a solid at the operating temperature of said connection.
